UNITED STATES PATENT OFFICE.

WALES E. VAN AME, OF FORT WAYNE, INDIANA.

MANIFOLDING SALES-BOOK.

SPECIFICATION forming part of Letters Patent No. 650,284, dated May 22, 1900.

Application filed October 23, 1899. Serial No. 734,469. (No model.)

To all whom it may concern:

Be it known that I, WALES E. VAN AME, a citizen of the United States, residing at Fort Wayne, in the county of Allen, in the State 5 of Indiana, have invented certain new and useful Improvements in Duplicating Sales-Checks; and I do hereby declare that the following is a full, clear, and exact description of the invention, which will enable others 10 skilled in the art to which it appertains to make and use the same, reference being had to the accompanying drawings, which form part of this specification.

My invention relates to improvements in 15 duplicating sales check-books, which are also adapted to be employed by traveling salesmen as an order-book and by railway-offices for shipping-bills.

The object of my invention is to provide an 20 improved duplicating sales check-book so arranged that both the original and the duplicating check, which are preferably differently colored, can be simultaneously extracted without first separating the intervening carbon-sheet, which is arranged at the center of the book.

The principal novel feature of my present 25 improvement is the construction whereby the original and duplicating checks can be simultaneously detached without the necessity of first separating the intervening copying carbon-sheet.

In the accompanying drawings, in which 30 similar reference-numerals indicate like parts, Figure 1 is a perspective view of my improvement closed, showing the relative arrangement of the two sets of sales-checks and the thumb-notch in the lower set to facilitate the opening of the book at the desired place. Fig. 40 2 is a perspective of the same fully opened at the place next to be used, the original sales-check next to be used being cut away in part to show the underlying copying-carbon. Fig. 3 is an enlarged detail of the upper edge of 45 the book, showing the manner of securing the sales-checks together and the manner of securing the copying-carbon and also showing the flexible connection of the book-cover sections. Fig. 4 is a perspective detail of the 50 upper edge of the book closed, broken away in part to show the arrangement of the wire fasteners which secure the detachable check

in position. Fig. 5 is a detail of the said fasteners.

The sales-checks 1, preferably fifty in number, are ruled in the usual manner for name of purchaser, street, number, and the number of the sales person. Where my improvement is used for a traveling-salesman's order-book or for railway shipping-bills, the checks 55 60 are of course provided with the proper printed matter which will adapt them for such use. The checks are also ruled in the usual manner, name of articles purchased and the selling-price of the same, and are also provided 65 at the bottom with the card of the firm from whom the purchase was made, as shown in Fig. 2, if so desired. The duplicate checks 2, equal in number with the said checks 1, are preferably of a differently tinted or colored 70 paper and have the ruling and printing thereon an exact duplicate of that on the said original sales-checks and are of the same size as the overlying original checks.

The carbon copying-sheet 3 is arranged between the inner and adjacent original and duplicate checks and is of a length equal to the ruled portion of the said checks, Fig. 2, whereby the operator can detach the adjacent sheets 1 and 2 by seizing the bottom 80 thereof without first separating the said intervening carbon. This carbon-sheet has its upper edge provided with a strong narrow strip of canvas 7, which serves two purposes—viz., to so strengthen the said upper end that 85 it will not readily tear out or become detached from its position in use, and it more distinctly separates the original and duplicate sets of sales-checks, and thereby facilitates the opening of the book at the center thereof. The 90 duplicate checks being of greater length than the intervening carbon, it is only necessary to catch hold of the two checks by their outer ends, and they can be quickly detached without in any manner interfering with the carbon, which is not the case where the carbon 95 is of the same or approximately the same length as the checks. By this construction a great saving of time is effected, for it is not necessary to tear off the checks separately, 100 as has generally been the case heretofore. The said original sales and duplicate checks and copying carbon-sheet thus arranged are secured together by a plurality of (prefer-

ably three) small wires 5, which pass through suitable registering perforations in the upper ends of said sheets and then have their ends united or bent into parallel relation, as shown in Figs. 4 and 5. These fasteners 5 also pass through a proper cover of suitable material formed of two parts 6, the size of which corresponds to that of the said checks. These cover-sections 6 are connected at their upper or adjacent ends by a flexible strip 4, of cloth or other suitable material, whereby my improved book can be laid open for use in the manner shown in Figs. 2 and 3, without any tendency toward binding, in a well-understood manner.

The wire fasteners 5 are made in the form of a narrow loop, as shown, and of sufficient length to project somewhat at each end beyond the cover-sections 6, as shown in Figs. 1 and 4. This is an important feature of my invention, for the reason that the projecting loop ends of the fasteners permit the book to be so opened as to have the adjacent ends of the checks out of contact, as shown in Fig. 2, thereby avoiding all tendency toward binding when in use.

As the free ends of the fasteners are arranged upon the outer face of the upper end of the book, they can in no way interfere with the free movement of the said checks and cover-sections on the fasteners in opening and closing the book. The back thus formed is secured to the said checks by the said wires 5, which also pass through perforations in the said sections 6. The lower cover-section 6 and the said duplicate sales-checks are provided with a thumb-notch 8, Fig. 1, to facilitate opening the book at the carbon when it is desired to make an entry therein. While this thumb-notch may be omitted without affecting the spirit of my invention, its use is a convenience, though not a necessity.

Both the original and duplicate checks 1 and 2 are consecutively numbered from one to fifty and are simultaneously detached after each entry thereon, as described. If desired, the inside of one of the cover-sections may be

provided with a summary blank for fifty entries, corresponding with the number of sales-checks, to facilitate checking up each sales-person's book at the close of each day's sales. While this feature is a convenient accessory, it is not at all essential to my invention.

Having thus described my invention, what I desire to secure by Letters Patent is—

1. In a duplicating sales-book, the two covers, the duplicate checks, and the intermediate carbon of less length than the duplicating-checks so that the checks can be simultaneously removed in pairs without interfering with the carbon, and which carbon is provided with a strip of canvas, combined with a series of oval metallic fasteners which have their ends disconnected so that they are free to accommodate themselves to the movement of the leaves for opening and closing the book and whereby the leaves are made to lie flat when the book is opened out, substantially as shown.

2. In a book, a metallic fastening formed from a single piece of wire, which is bent upon itself so as to form an elongated figure having one curved and one straight side, the ends of the wire upon the straight side overlapping each other, substantially as specified.

3. A duplicating-book consisting of two sets of sheets or checks provided with an intermediate copying-carbon shortened as described for the purpose specified, whereby a sheet or check of each set can be simultaneously detached without first separating said carbon therefrom; a plurality of oval metallic fasteners arranged as shown, whose projecting overlapping ends are adapted to prevent binding of said leaves or checks when the book is opened; and a proper cover.

Signed by me at Fort Wayne, Allen county, State of Indiana, this 20th day of October, 1899.

WALES E. VAN AME.
